DESIGN.

J. S. TIMMONS.

WALL TELEPHONE SET.

APPLICATION FILED SEPT. 14, 1918.

53,540.

Patented July 8, 1919.

Inventor

John S. Timmons

By his Attorney

Howard D. Key

UNITED STATES PATENT OFFICE.

JOHN S. TIMMONS, OF NEW YORK, N. Y.

DESIGN FOR A WALL TELEPHONE SET.

53,540.

Specification for Design.

Patented July 8, 1919.

Application filed September 14, 1918. Serial No. 254,141. Term of patent 14 years.

To all whom it may concern:

Be it known that I, JOHN S. TIMMONS, a citizen of the United States, residing in New York city, county and State of New York, have invented a new, original, and ornamental Design for a Wall Telephone Set, of which the following is a specification, reference being had to the accompanying drawing, which forms a part of this application, and in which the single figure is a front elevation of a wall telephone set embodying my design.

In the drawing the box-like container 1

is of semi-circular ended, elongated rectangular contour. The cover plate conforms in contour with the container. Window closures 3 and 4 have perforations and margins circularly disposed and are located on opposite sides of a switch plate 5, which mounts each projecting switch-key 6. Many of the parts and projections have a curved contour.

I claim:

The ornamental design for a wall telephone set, as shown and described.

JOHN S. TIMMONS.
